US0D1009053S

(12) **United States Design Patent** (10) Patent No.: **US D1,009,053 S**
(45) Date of Patent: ** Dec. 26, 2023

(54) **MOBILE PHONE WITH GRAPHICAL USER INTERFACE**

- (71) Applicant: **Samsung Electronics Co., Ltd.**, Suwon-si (KR)
- (72) Inventors: **Eun Sun Chae**, Seoul (KR); **Minsoo Kwon**, Seoul (KR); **Aejung Seo**, Seoul (KR)
- (73) Assignee: **SAMSUNG ELECTRONICS CO., LTD.**, Suwon-si (KR)

(**) Term: **15 Years**

(21) Appl. No.: **29/733,227**

(22) Filed: **Apr. 30, 2020**

Related U.S. Application Data

- (62) Division of application No. 29/689,741, filed on May 1, 2019, now Pat. No. Des. 883,306, which is a division of application No. 29/603,896, filed on May 12, 2017, now Pat. No. Des. 883,299.

(30) **Foreign Application Priority Data**

Feb. 22, 2017 (KR) 30-2017-0008420

CLAIM

The ornamental design for a mobile phone with graphical user interface, as shown and described.

DESCRIPTION

FIG. 1 is a front perspective view of a mobile phone with graphical user interface showing our new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.

The broken lines in the figures depict portions of the mobile phone with graphical user interface that form no part of the claimed design.
